UNITED STATES PATENT OFFICE

SHELBY V. KNEPPER, OF TOLEDO, OHIO, ASSIGNOR TO OWENS-ILLINOIS GLASS COMPANY, OF TOLEDO, OHIO, A CORPORATION OF OHIO

DESIGN FOR A JAR

Application filed July 30, 1931. Serial No. 46,786. Term of patent 14 years.

To all whom it may concern:

Be it known that I, SHELBY V. KNEPPER, a citizen of the United States, residing at Toledo, in the county of Lucas and State of Ohio, have invented a new, original, and ornamental Design for Jars, of which the following is a specification, reference being had to the accompanying drawings, forming a part hereof.

In the drawings:

Fig. 1 is a side elevational view of a jar showing my design embodied therein.

Fig. 2 is a view looking toward one corner of the jar.

Fig. 3 is a top plan view thereof.

I claim:

The ornamental design for a jar substantially as shown.

Signed at Toledo, in the county of Lucas and State of Ohio, this 25th day of July, 1931.

SHELBY V. KNEPPER.
